[57] ABSTRACT

A slide fastener comprises a synthetic-resin monofilament formed into undulations or turns and attached by a chain stitch to the support tape at only the legs lying along this tape. These legs are embraced by the stitches which are in part shielded by the remainder of the coupling element. The stitches may simultaneously form a filler cord and may be locked in place by clamping of the shanks of the coupling element thereagainst.

SLIDE FASTENER STRINGER

FIELD OF INVENTION

My present invention relates to slide fasteners and, more particularly, to a slide fastener having continuous coupling elements of the meandering or coil type which are affixed to respective support tapes by rows of stitching.

BACKGROUND OF THE INVENTION

Slide fasteners have been provided heretofore with support tapes upon which are mounted respective rows of coupling elements which are mutually engageable and disengageable upon the movement of a slider therealong. The coupling elements may be coils or meanders provided with closely spaced coupling heads adapted to engage between the coupling heads of the opposed element and produced, for example, from a continuous synthetic-resin monofilament, e.g. a thermoplastic, such as a polyamide (nylon) or a polyester.

The tapes or support bands have been composed of synthetic resin or fabric and may be knitted or woven. Furthermore, various forms of attachment have been used heretofore to affix each coupling element along the edge of the respective support tape of the slide-fastener half. For example, knitted support tapes may have the coupling elements incorporated into the fabric by knitting loops therearound or by providing openings in the fabric into which the heads of the coupling element are inserted. Woven support tapes may include the coupling element as a wrap thread and may provide weft threads in engagement with the bights interconnecting the coupling heads of the particular element.

More frequently, however, the coupling elements are secured by rows of stitching, especially chain stitching, which passes over the shanks of each turn or meander of the coupling element and may, if desired, form a guide for the slider. Such systems have, however, the disadvantage that movement of the slider back and forth along the rows of the coupling head or along the coupling elements causes wear of the stitching affixing the coupling elements to the support tape and eventual deterioration of the slide fastener. Furthermore, since the rows of stitching are exposed, they are subject to breakage and, indeed, the deterioration of the system by which the coupling elements are affixed to the support tape, is a prime cause of breakdown of the slide fastener.

Mention may also be made, at this point, to the use of filler cords within the coupling element coil, in many cases, the rows of stitching passing through this cord. Also the stitching securing a coupling element to the support tape may include stitch loops which pass through a cord lying alongside the coupling element (i.e. along a flank thereof opposite the coupling heads) and engaging loops of the meander or coil from which the coupling element is constituted. Systems in which the coupling element is knitted or woven into the support tape are, of course, of expensive manufacture whereas arrangements using filler cords have likewise been complex in prior-art constructions of the slide-fastener stringers. As a result, principal attention has been directed heretofore to the attachment of the coupling elements by rows of stitches and, particularly, by chain stitching described earlier. Such stitching has the advantage that it can be relatively fine, thereby ensuring a close spacing of the coupling heads of similar fineness as is desirable in so-called invisible slide fasteners and wherever a no-snag high-quality closure is required. However, it has been found that the loops of the chain stitching which engage the shanks of the coupling elements and, especially those shanks which are spaced from the support tape, have a tendency to slide rearwardly over the bight of the loops of the coupling element and loosen, while those stitches which overlie the coupling element, are subject to wear as indicated above. As a result, the conventional methods of affixing continuous coupling elements to support tapes in slide-fastener stringers have many defects which have not been eliminated by prior-art systems.

OBJECTS OF THE INVENTION

It is, therefore, the principal object of the present invention to provide an improved slide fastener wherein the above-mentioned disadvantages are obviated.

Another object of this invention is to provide a slide fastener utilizing continuous coupling elements, namely, coils or meanders of monofilament synthetic resin, which provides a more secure attachment of the coupling element to the support tape.

It is also an object of the present invention to provide a slide fastener having the advantages of a filler cord but in which the filler cord, as a separate entity, may be avoided.

Yet a further object of the invention is the provision of a slide fastener which will not manifest loosening of the attachment of the coupling element upon breakage of a small number of attachment loops or the breakage of the attachment thread.

It is an object of the invention further, to provide a slide fastener of the character described in which movement of the slider along the coupling elements cannot wear away the attachment stitches.

SUMMARY OF THE INVENTION

These objects and others which will become apparent hereinafter, are attained, in accordance with the present invention, with a slide-fastener stringer which comprises a pair of support tapes and a respective continuous coupling element lying along an edge of the support tape and so arranged and constructed that each coupling head of the continuous coupling element is associated with at least one shank which lies against the support tape; the means for attaching the coupling element to the respective support tape includes a row of chain stitching with a loop thereof engaging each of the shanks resting upon the support tape and passing through the tape on opposite sides thereof while the loop itself lies within the coil space. In other words, each coupling element also provides shank portions of its turns or meanders which lie above the shank portions seized by the aforementioned loops to define an interior of the coil or meander through which the thread of the chain stitching passes. No threads of the chain stitching lie above the portions of the coupling elements most distal from the support tape.

The invention will probably be best understood in terms of a coupling element in the form of a coupling coil, the latter being generally a helix which may be somewhat distorted so that each turn forms an ellipse, ovoid, keyhole or like shape. However, the invention is applicable to meanders of the type having a space through which the chain stitching may pass. With coupling coils, each turn will have a shank lying against the fabric of the support tape and a shank spaced thereabove connected with the first-mentioned shank by a bight set inwardly from the edge of the support tape and with the lower shank of the next turn by a coupling head. The chain stitching of the present invention passes through the interior of the coil and engages only the shanks in contact with the support tape, i.e. the lower shanks.

According to a specific feature of this invention, the chain stitching is a single-thread chain stitch, i.e. a form of chain stitching in which, as the needle is passed through the fabric, a loop former engages the thread on the opposite side of the fabric from that through which the needle is thrust. The loop former retains the loop until, at the next stitch, the needle again carries the thread through this loop and at the same time pays out a fresh loop to be engaged by the loop former. When chain stitching of this type is used, the successive loops of the chain stitch engage around and partially cover the shanks of the coupling element which lie against the support tape so that the entire seam is concealed within the coupling element.

As a consequence, wear of the chain stitching is obviated and the attachment stitching is fully concealed. Since the stitches cannot slip off the coupling element, loosening is not a problem.

According to still another feature of this invention, the shanks of the coupling element are clamped around and engage or are thermally bonded to the threads of the row of chain stitching passing through the coupling element, the turns of the latter being appropriately deformed for this purpose. This clamping and bonding action further prevents loosening of the attachment stitches, even in the event of breakage of the attachment thread, since the thread cannot pull out of the eye formed by each turn. Moreover, the chain stitching fulfills the function of a filler cord within the coupling element and restricts compression of the latter.

DESCRIPTION OF THE DRAWING

The above and other objects, features and advantages of the present invention will become more readily apparent from the following description, reference being made to the accompanying drawing in which:

FIG. 1 is a diagrammatic perspective view illustrating the formation of a slide fastener in accordance with the principles of the present invention;

FIG. 2 is a cross-sectional view illustrating the clamping engagement of the chain-stitch threads in accordance with the present invention;

FIG. 3 is a detail view showing other aspects of the formation of the slide fastener;

FIG. 4 is a view similar to FIG. 3 of another embodiment, and FIG. 5 is a view of a portion of the slide-fastener half according to the invention.

SPECIFIC DESCRIPTION

In the following description, I have referred to a method of and an apparatus for producing the slide fastener in accordance with the present invention. This method and apparatus are more fully described and are claimed in the commonly assigned copending application Ser. No. 93,273 filed concurrently herewith by myself and Karl Griesbaum and entitled *METHOD OF AND APPARATUS FOR PRODUCING SLIDE-FASTENER STRINGERS*.

In FIGS. 1 and 2 of the drawing, I have shown generally diagrammatically the principles of the present invention as applied to a helical coil coupling element and the slide-fastener stringer incorporating same.

Basically, the stringer comprises a pair of slide-fastener halves, each of which has a fabric support tape 1, a coil-tape continuous coupling element 2 composed of a synthetic-resin monofilament, and attachment means in the form of a row 3 of general stitches traversing the support tape 1. The coupling element, in turn, is formed with a plurality of coupling members generally designated at 4 and comprising coupling heads 7 projecting beyond the edge 1a of the tape. The heads 7 have outwardly projecting portions 7a and 7b adapted to engage behind similar portions of the heads of mating coupling members of the corresponding coupling element formed on the other tape of the stringer. The head 8 is provided by kinking the monofilament 2 at 8, for example, after a preliminary flattening of the filament. The shanks 6a and 6b extend rearwardly from each head 7 of a particular turn 4 and are joined by a bight 9 to the turn of a succeeding and preceding coupling head respectively. The shanks 6a lie against the tape 1 while the shanks 6b are disposed thereabove. Between the shanks and within the coil there is formed an eye-shaped space Oe constituting the interior of the coil.

As best seen in FIG. 1, moreover, the chain stitching is of the single-thread type wherein a loop 5 is formed above the tape 1 by thrusting the needle 40 of the chain-stitch sewing machine upwardly through the tape, a loop 31 being formed by engagement of a loop-former 42 with the thread as the needle is withdrawn. The loop 5, 31 is stretched over each shank 6a as it is laid in place upon the tape 1 and is engaged, in turn, by the upwardly carried thread of the needle which, upon its subsequent introduction through the tape, passes through this loop. Hence, a double strand of the thread of the chain stitch 3 overlies each of the shanks 6a and retains it against the tape

and passes through the latter on either side of the shank. The row 3 of chain stitches lies wholly within the interior Oe of the coupling-element coil and is shielded by the shanks 6b against deterioration.

As also can best be seen from FIGS. 1 and 2, each coupling member is held in place by a respective loop 5 of the chain stitch. In the conventional manner, end-stop members can be formed at the end of each coupling element, e.g. by the thermoplastic deformation of the coupling element and plug-and-socket members may be provided in the conventional fashion when separable slide fasteners are to be produced. The slider is applied in the usual manner, and upon movement along the coupling elements, brings both of the elements of the two slide-fastener halves into mating engagement or separates them from one another.

As best seen in FIG. 2, the upper shank 6b can be pressed downwardly, e.g. by a forming roller 43 which may be connected, as shown at 44, to a source of ultrasonic welding energy, while being constituted as an ultrasonic welding electrode or sonotrode. The shanks 6a and 6b are thereby clamped at 10 and thermally welded together against the two strands of the chain-stitch thread to lock each loop 5 and prevent release of the coupling element upon breakage of the stitch at any point 15 or against withdrawal of the single-thread chain stitch. The other member of the ultrasonic welding assembly can be an anvil underlying the tape as shown at 44. The ultrasonic welding operation simultaneously constitutes a thermal fixing of the coupling element in its deformed state as shown in FIG. 2.

The production of the slide fastener half according to the present invention is detailed at FIG. 3 which shows the apparatus in somewhat simplified form. It should be understood that the apparatus consists of an ordinary chain-stitch sewing machine and the various members of the apparatus, which are moved in synchronism, can be coupled with a cam drive of the sewing machine by conventional means. The apparatus comprises an upper transport comb 11 and a lower transport comb 12 which are periodically withdrawn, reinserted and shifted in the direction of arrow 17 and are provided with teeth 11a and 12a, respectively, engaging between the turns 4 of the coupling element.

To the main shaft of the chain-stitch sewing machine is connected, via an eccentric drive, the shaft 19 of a swinging lever 13, the axis of which is represented at A and lies parallel to the transport direction represented by the arrow 17 but which underlies the sewing machine table only partly illustrated at 18 in FIG. 3. The lever 13 is of generally C-shaped caliper or yoke configuration with a bent arm on 21 extending from below upwardly around the tape 30 and provided with an eye 22 through which the monofilament 2 is fed.

In addition, the apparatus comprises retaining fingers 14 and 15 which are mounted on pivoting shafts 14a and 15a respectively coupled with the cam drive and serving to retain the monofilament 2 during each swing of the arm 21 to and fro across the tape 30. The finger 15 thus forms the bight while the finger 14 forms the head of each coupling turn 4. Finger 14, moreover, may press with sufficient force to deform the head 7 as already noted. Assume, therefore, that the system is in the position illustrated in FIG. 3, i.e. with the needle 40 penetrating the tape 30 and forming the beginning of a loop 32 which is engaged by the loop former 31. At this instance, the filament 2 is stripped across the tape 30 and is retained by the finger 15 while the finger 14 preparatory impresses the filament to deform the latter preliminary to the return of the eye 22 in the counterclockwise direction. As the needle descends and disengages from the tape 30, the transport mechanism advances the tape in the direction of arrow 17 by a distance corresponding to one stitch and one turn of the coupling element, thereby stretching the loop 32 across the filament. The eye 22 then carries the filament again across the tape to form the upper shank as the needle is thrust upwardly to engage the loop. The process is repeated over the length of the support tape. The kink formed at 33 produces the head.

In FIG. 4, I show a system wherein in place of the finger 15, a mandrel M is employed in the shaping of the coupling coil. It will be understood, however, that similar principles can be used to produce meandering coupling chains. Furthermore, the apparatus can be doubled to form two slide-fastener halves simultaneously so that the opposing coupling elements can be interconnected in the production of the slide-fastener stringer. Each coupling element can be affixed to the respective support tape with several needles in, for example, the production of one-needle, two-needle, three-needle .... chain-stitch rows. The term "stitch," therefore, is not intended to limit the number of needles with which the stitches are formed. In FIG. 5, I show a finished portion of a slide-fastener half in which the upper shank of each turn is fused to the lower shank as described previously in connection with FIG. 2. The depressed rear portions of the upper shank can be seen clearly at 6b in this Figure.

The improvement described and illustrated is believed to admit of many modifications within the ability of persons skilled in the art, all such modifications being considered within the spirit and scope of the invention except as limited by the appended claims.

I claim:

1. A slide-fastener stringer half, comprising a support tape,

a continuous coupling element formed with a plurality of coupling members matingly engageable with the coupling members of an opposing slide fastener half and having respective shanks lying along said tape, a row of chain stitches fastening said coupling element to said tape and including a respective loop extending over each of said shanks, said coupling element being a coil of a synthetic-resin monofilament and each of said members of said coil includes a coupling head, a lower shank extending from said head along said tape and an upper shank extending from said head above said lower head and defining the interior of said coil, said loops passing over only said lower shank and said row being formed within the interior of said coil.

2. The slide-fastener stringer half defined in claim 1 wherein said row of chain stitches is a single-thread chain stitch and each of said loops has two strands engaging the respective lower shank.

3. The slide-fastener stringer half defined in claim 2 wherein each of said upper shanks clamps a respective loop against the corresponding lower shank.

4. The slide-fastener stringer half defined in claim 3 wherein each of said upper shanks is fused to the respective lower shank in the region in which said loop is clamped.
